FASTENER DRIVING APPARATUS

Oscar A. Wandel, Mundelein, and Richard H. Doyle, Mount Prospect, Ill., assignors to Fastener Corporation, Chicago, Ill., a corporation of Illinois

Filed Feb. 16, 1959, Ser. No. 793,536

12 Claims. (Cl. 121—13)

This invention relates to a fluid operated device for driving fasteners and, more particularly, to such a device including new and improved means for pneumatically actuating a fastener driving piston.

In most pneumatically operated tackers, staplers or nailers, a fastener is driven into a workpiece by a single power stroke of a blade actuating piston, which power stroke is initiated by the abrupt admission of a large body of compressed air into a cylinder under the control of manually or automatically actuated valve means. In some prior tools, the piston and the blade are returned to a normal position following the completion of the power stroke by a compression spring that is interposed between the lower end of the piston and the nose of the tacker. This arrangement has the disadvantages that the spring sometimes breaks and that the provision of the space required for the compression spring unduly increases the size of the gun and requires the blade to be located near the axis of the piston. To overcome these deficiencies, pneumatic means have been devised for restoring the piston to its normal position. To pneumatically actuated fastener driving tools which include both improved pneumatic driving means and a pneumatic piston return mechanism are shown and described in the copending application of Richard H. Doyle, Serial No. 642,143, filed February 25, 1957, now Patent No. 2,944,522, and in the copending application of Oscar A. Wandel and Richard H. Doyle, Serial No. 683,170, filed September 10, 1957, now Patent No. 2,979,725. However, it would be desirable to improve the reliability of operation of these tackers over a wider range of air pressure as well as to provide a tacker construction that is more economical to manufacture and easier to assemble.

Accordingly, one object of the present invention is to provide a new and improved fluid powered fastener driving apparatus.

Another object is to provide a fastener driving tool including new and improved pneumatic means for actuating a fastener driving blade.

Another object is to provide a fastener driving tool including new and improved means for supplying compressed air to a cylinder to actuate a piston.

A further object is to provide a pneumatically actuated tool including novel means for exhausting compressed air from a cylinder.

Another object is to provide a new and improved piston and blade assembly in which the position of the blade relative to the piston can be easily adjusted.

Another object is to provide a pneumatically actuated hand tacker that is more easily manufactured and assembled.

In accordance with these and many other objects, an embodiment of the invention comprises a housing which has an open upper end and which defines both a lower chamber of lesser diameter and an upper chamber of greater diameter to which compressed air is supplied. A cylinder is slidably mounted in the uppermost chamber and slidably receives the flanged upper end of a piston, the lower portion of which is slidably mounted in the lower chamber. A fastener driving blade is secured to the lower end of the piston displaced from the axis thereof. The upper opening in the housing is sealed by a closure cap to which an annular resilient valve seat is secured by a flanged member forming a part of an ex-

2

haust valve assembly. This member includes an axially extending passageway which is aligned with the axis of the piston and which provides an exhaust passageway for the upper portion of the cylinder. A spring carried on the member biases an exhaust valve element toward a position closing this passageway to seal off communication between the atmosphere and the uppermost chamber. A valve operator secured to the valve element extends into the upper chamber and is adapted to be engaged by the upper end of the cylinder to move the valve element so that the exhaust valve assembly is opened.

In the normal condition of the pneumatically actuated tool, a manually controlled valve and a safety valve assembly are in a normal condition in which compressed air derived from a reservoir formed in a hollow handle of the housing is supplied to the lower end of the upper chamber. This compressed air acts on the lower end of the cylinder to pneumatically bias the upper end of the cylinder into engagement with the valve seat, thereby to seal off communication between the upper end of the interior of the cylinder and the upper chamber. In this position, the upper end of the cylinder also engages the valve operator to operate the exhaust valve assembly to an open condition in which the upper portion of the interior of the cylinder is in communication with the atmosphere. The compressed air at the lower end of the upper chamber also enters the lower portion of the cylinder and acts on the flanged portion of the piston to pneumatically maintain the piston in an uppermost position adjacent the upper end of the cylinder.

When manually controlled valve and the safety valve assembly are both actuated, the compressed air supplied to the lower portion of the upper chamber is cut off, and this portion of the upper chamber is connected to the atmosphere. This exhausts the compressed air from the lower portion of the cylinder and produces a pressure differential across the cylinder so that the cylinder is moved downwardly out of engagement with the valve seat. As the cylinder moves downwardly, the spring in the exhaust valve assembly shifts the valve element into engagement with a valve seat to close the exhaust valve. Further, as the cylinder moves downwardly, the upper portion of the interior of the cylinder is abruptly placed in communication with the large body of compressed air contained in the upper chamber so that the piston is driven downwardly in a power stroke during which the fastener driving blade engages and drives a fastener supplied by a suitable magazine.

When the safety valve assembly and the manual valve are released, compressed air is again supplied to the lower portion of the chamber. This compressed air produces an upwardly directed force acting on the cylinder to again shift the upper end of the cylinder into seating engagement with the valve seat so that communication between the upper chamber and the interior of the cylinder is closed off. Further, in moving upwardly, the upper end of the cylinder engages the valve operator element to open the exhaust valve assembly. The compressed air entrapped in the upper end of the cylinder is then exhausted so that the piston is elevated to its normal position by the compressed air supplied to the lower end of the upper chamber. Thus, in response to each momentary actuation of the safety valve assembly and the manual valve, the piston is driven downwardly in a power stroke during which a fastener is driven into a workpiece and the piston is then pneumatically returned to its normal position.

Many other objects and advantages of the present invention will become apparent from the following detailed description when considered in conjunction with the drawings in which:

FIG. 1 is a fragmentary sectional view of a pneu-

matically operated tacker which embodies the present invention and which is illustrated in its normal position; and

FIG. 2 is a fragmentary sectional view similar to FIG. 1 showing the tacker in its position at the completion of a power stroke.

Referring now more specifically to the drawings, there-in is shown a pneumatically operated fastener driving tool, indicated generally as 10, which includes a housing 12 having an open end and defining a lower cylindrical chamber 14 of lesser diameter and an upper cylindrical chamber 16 of greater diameter. Compressed air is supplied to the upper chamber 16 from a reservoir formed by a hollow handle (not shown) in the housing 12 through an enlarged passageway 18. A cylinder 20 that is slidably mounted in the upper chamber 16 slidably receives the upper portion of a piston 22, the lower portion of which is slidably mounted in the chamber 14. A fastener driving blade 24 secured to the lower end of the piston 22 is adapted to engage and drive fasteners, such as staples or nails, supplied by a suitable magazine (not shown). The open upper end of the chamber 16 is closed by a removable closure cap 26 on which a resilient valve seat 28 and an exhaust valve assembly 30 are carried.

In the normal condition of the tool 10, a safety valve assembly 32 and a manually controlled valve assembly 34 are both in a released condition so that compressed air is supplied to the lower end of the chamber 16 from the passageway 18. This compressed air forces the cylinder 20 to its uppermost position in which its upper end engages the valve seat 28 to close off communication between the interior of the cylinder 20 and the chamber 16. In this position, the upper end of the cylinder 20 also actuates the exhaust valve assembly 30 to an open condition in which the atmosphere is in communication with the interior of the cylinder. The compressed air supplied to the lower end of the chamber 16 also acts on the piston 22 to hold it in an elevated or normal position.

When the two valve assemblies 32 and 34 are actuated, compressed air is no longer supplied to the lower end of the chamber 16 and this portion of the chamber is connected to the atmosphere. This produces a downwardly acting force differential across the cylinder 20 so that the cylinder moves downwardly away from the closure cap 26. In moving downwardly, the upper end of the cylinder 20 permits the exhaust valve assembly 30 to close to prevent the compressed air in the upper portion of the chamber 16 from escaping to the atmosphere and also moves out of engagement with the valve seat 28 so that compressed air from the chamber 16 enters the cylinder 20 to force the piston 22 downwardly. During this power stroke, the lower end of the drive blade 24 engages and sets a fastener.

The piston 22 remains in this displaced or lower position until such time as both of the valve assemblies 32 and 34 are released. The release of these valve assemblies supplies compressed air to the lower portion of the chamber 16 from the passageway 18 so that the cylinder 20 is again moved upwardly to engage the valve seat 28 and to close the exhaust valve assembly 30 so that the interior of the cylinder 20 is placed in communication with the atmosphere. The venting of the upper portion of the cylinder 20 together with the provision of compressed air to the lower portion of the interior of this cylinder elevates the piston 22 to its normal position. The tool 10 remains in this condition until both of the valve assemblies 32 and 34 are next actuated.

Referring now more specifically to the housing 12, which may be cast of a suitable material such as aluminum or magnesium, the lower cylindrical chamber 14 is formed with a diameter suitable to slidably receive a lower portion of the piston 22. The lower end of the chamber 14 is provided with a resilient bumper 36 for cushioning the termination of the power stroke of the

piston 22. The resilient bumper 36 is provided with a notched or grooved portion 38 for receiving the driver blade 24, and the lower end of the housing 12 is also provided with an opening 40 aligned with the notch 38 to permit air to be exhausted from the chamber 14 when the piston 22 moves downwardly. The upper end of the chamber 14 is connected to the lower end of the chamber 16 by an annular wall surface 42 which serves as a stop to limit downward movement of the cylinder 20.

10 To provide a means for slidably mounting the cylinder 20 within the upper chamber 16, a sleeve 44 is secured within the chamber 16 to rest on an annular shoulder 46. One resilient O-ring 48 carried on the sleeve 44 provides a seal between the inner wall of the chamber 16 and the outer wall of the sleeve 44, and another resilient O-ring 50 carried on the sleeve 44 provides a seal between the inner wall of the sleeve 44 and the outer wall of the cylinder 20. The cylinder 20 is slidably mounted within the sleeve 44 and includes a lower annular flanged portion 20a which is located between the lower end of the sleeve 44 and the annular wall 42. A resilient O-ring 52 carried on the flanged portion 20a provides a seal between the inner wall of the chamber 16 and the flanged portion of the cylinder 20. The annular space bounded by the 15 lower end of the sleeve 44 and the upper surface of the flanged portion 20a is continuously connected to the atmosphere through an opening 54 in the housing 12.

20 In the normal condition of the tool 10, a safety valve assembly 32 and a manually controlled valve assembly 34 are both in a released condition so that compressed air is supplied to the lower end of the chamber 16 from the passageway 18. This compressed air forces the cylinder 20 to its uppermost position in which its upper end engages the valve seat 28 to close off communication between the interior of the cylinder 20 and the chamber 16. In this position, the upper end of the cylinder 20 also actuates the exhaust valve assembly 30 to an open condition in which the atmosphere is in communication with the interior of the cylinder. The compressed air supplied to the lower end of the chamber 16 also acts on the piston 22 to hold it in an elevated or normal position.

cylinder 20 is shifted to its displaced position (FIG. 2), the upper end of the cylinder 20 moves out of engagement with the valve operator plate 75 so that the compression spring 70 shifts the valve element 66 into engagement with the O-ring 74. This closes the passageway 68 to prevent compressed air in the chamber 16 from escaping to the atmosphere. Thus, the exhaust valve assembly 30 is selectively actuated to opened and closed conditions in accordance with the positions of the shifting cylinder 20.

Referring now more specifically to the piston 22, an upper flanged portion 22a thereof is slidably mounted within the cylinder 20, and a resilient O-ring 82 carried on the flanged portion 22a seals the interface between the inner wall of the cylinder 20 and the piston 22. The lower end of the piston 22 is slidably received within the chamber 14 and carries a resilient O-ring 84 for sealing the interface between the piston 22 and the wall of the chamber 14. The driver blade 24 is secured to the lower end of the piston 22 at a position displaced from the axis thereof by an element 86 which is brazed or welded to the driver blade 24 at its lower end and which is threaded at its upper end to be secured within an internally threaded aperture 88 formed in the lower end of the piston 22. Thus, the effective length of the blade 24 can be adjusted by merely rotating this blade prior to the insertion of the piston 22 into the tacker 10. Since the generally flat blade 24 is held against rotation by engaging the walls of the drive track shown in the above identified copending application and since the blade 24 is threadedly secured to the piston 22 at a point radially displaced from the axis thereof, relative rotary movement between the piston 22 and the blade 24 is prevented so as to prevent any change in the adjusted length of the blade after the blade and the piston have been inserted into the tacker 10. The upper end of the piston 22 includes a recess 90 for receiving the lower end of the valve element 66 and the nut 77 so that the upper end of the piston 22 can engage the valve operator 75 to limit upward movement of the piston.

As indicated above, the safety valve assembly 32 and the manually actuated valve assembly 34 control the selective shifting of the position of the cylinder 20 so as to control the operation of the pneumatically actuated tool 10. These two valve assemblies are illustrated in part in the drawings and preferably are of the constructions disclosed in detail in the above identified copending Wandel and Doyle application. The safety valve assembly 32 includes a valve stem 92 that is slidably mounted within a bore 94 formed in the housing 12. An O-ring 99 carried on the stem 92 seals the interface between the stem and the wall of the bore 94. With the valve stem 92 in the position shown in FIG. 1, compressed air from the passageway 18 passes through the upper portion of the bore 94 and into the lower end of the chamber 16 through a port 96. When the valve stem 92 is elevated to the position illustrated in FIG. 2 by placing the nose of the tool 10 adjacent a workpiece, a recessed portion 98 on the stem 92 is moved into alignment with the port 96 and a passageway 100 so that compressed air now flows into the lower portion of the chamber 16 through a port 102, a portion of a bore 104, the passageway 100, the notched portion 98, and the port 96.

The port 102 and the bore 104 form a part of the manually controlled valve assembly 34. Thus, the actuation of the safety valve assembly 32 to the position shown in FIG. 2 places the operation of the tacker 10 under the control of this valve assembly. The manually controlled valve assembly 34 includes a sleeve 106 which is mounted within the lower end of the bore 104 and which is provided with an axially extending passageway 108. The passageway 108 is normally closed by a ball valve element 110 which is maintained in seating engagement with a resilient O-ring 112 by the pressure of the compressed air supplied through the port 102. However, when the

ball valve 110 is lifted out of engagement with the O-ring 112 and into the position illustrated in FIG. 2 in which the port 102 is closed, the lower end of the chamber 16 is no longer supplied with compressed air from the passageway 18 and is connected to the atmosphere through the port 96, the notched portion 98, the passageway 100, the upper portion of the bore 104, and the passageway 108. Exhausting the lower portion of the chamber 16 shifts the cylinder 20 downwardly so that the exhaust valve assembly 30 is closed and compressed air is admitted to the upper end of the cylinder 20 to drive the piston 22 downwardly. When the tool 10 is lifted from the workpiece so that the valve stem 92 is restored to the position shown in FIG. 1 by resilient biasing means (not shown) or when the deflecting force is removed from the ball valve element 110 so that this element again engages the O-ring 112, compressed air is again supplied to the lower end of the chamber 16. This restores the cylinder 20 to the position illustrated in FIG. 1 and opens exhaust valve 30 so that the piston 22 can be elevated to the position shown in FIG. 1 by the compressed air supplied to the lower end of the chamber 16. Thus, the automatically actuated safety valve assembly 32 and the manually actuated valve assembly 34 control the operation of the pneumatically actuated tool 10.

Referring now more specifically to the operation of the pneumatically actuated fastener driving tool 10, in the normal condition thereof compressed air is supplied from the reservoir defined by the hollow handle (not shown) through the enlarged passageway 18, the bore 94, and the port 96 to the lower end of the chamber 16. The compressed air admitted into the lower end of the chamber 16 is contained in the space bounded by the sealing O-rings 52, 82 and 84. This body of compressed air serves to hold the cylinder 20 in its normal position (FIG. 1) in which the upper end thereof engages the valve seat 28 to seal off communication between the chamber 16 and the upper end of the interior of the cylinder 20. Further, in this normal position, the valve operator plate 75 is engaged by the upper end of the cylinder 20 to open the exhaust valve assembly 30 so that the upper portion of the interior of the cylinder 20 is connected to the atmosphere. The upwardly directed component of force for maintaining the cylinder 20 in this normal position is due to the differential effective upper and lower areas on the cylinder 20. More specifically, since the annular area of the upper surface of the flange 20a on the cylinder 20 is connected to the atmosphere through the opening 54, the annular lower surfaces of the cylinder 20 and of the flanged portion 20a which are exposed to the compressed air is greater than the effective annular upper area of the upper end of the cylinder 20. Since both of these areas are exposed to compressed air of the same pressure, the greater effective lower area produces an upwardly directed component of force for seating the upper end of the cylinder 20 on the valve seat 28 and for also overcoming the force applied to the cylinder by the compression spring 70.

The compressed air admitted to the lower end of the chamber 16 also serves to maintain the piston 22 in its normal position adjacent the upper end of the cylinder 20. More specifically, the upper portion of the interior of the cylinder 20 is connected to the atmosphere through the exhaust valve assembly 30 which has been actuated to an open condition by the movement of the cylinder 20 to its normal position. The compressed air contained in the lower portion of the cylinder 20 acts on the effective lower surface of the flanged portion 22a to provide an upwardly directed component of force which holds the upper end of the piston in engagement with the lower surface of the valve operator plate 75.

When the tool 10 is to be operated, the nose thereof is placed in engagement with a workpiece so that the safety valve assembly 32 is actuated to move the valve stem 92 through the bore 94 to a position in which the notched

portion 98 is interposed between the passageway 100 and the port 96. In this position, the upper end of the valve stem 92 closes off communication between the bore 94 and the port 96 so that compressed air no longer can be supplied to the lower end of the chamber 16 through the bore 94. However, in this position, the supply of compressed air to the lower end of the chamber 16 is maintained through the port 96, the notched portion 98 on the valve stem 92, the passageway 100, the upper end of the bore 104, and the port 102. A suitable manual control means, such as a trigger assembly, is then operated to move the ball valve element 110 upwardly from the position shown in FIG. 1 to the position shown in FIG. 2. In this position, the ball valve 110 closes the port 102 so that compressed air is no longer supplied to the lower end of the chamber 16. In moving to this position, the ball valve element 110 moves out of engagement with the O-ring 112 so that the lower end of the chamber 16 and the lower end of the interior of the cylinder 20 are connected to the atmosphere through the port 96, the notched portion 98, the passageway 100, a portion of the bore 104, and the passageway 108.

When the lower end of the chamber 16 is returned to atmospheric pressure, the compressed air in the upper portion of the chamber 16 acting on the effective upper surface of the cylinder 20 provides a downwardly directed component of force that moves the cylinder 20 downwardly until the lower end thereof engages the annular wall 42. This downward movement of the cylinder 20 operates the exhaust valve assembly 30 to a closed condition so as to prevent the compressed air in the upper portion of the chamber 16 from being exhausted to the atmosphere. More specifically, as the upper end of the cylinder 20 moves downwardly to the position shown in FIG. 2 and out of engagement with the valve operator plate 75, the compression spring 70 moves the valve element 66 downwardly until it engages the O-ring 74. This closes the passageway 68 to prevent communication between the chamber 16 and the atmosphere.

When the upper end of the cylinder 20 moves out of engagement with the resilient valve seat 28, a large volume of air is abruptly admitted to the upper end of the interior of the cylinder 20 to drive the piston 22 downwardly in a power stroke that is terminated by the engagement of the lower end of the piston 22 with the resilient bumper 36. During this downward movement, the air entrapped in the lower end of the chamber 14 is exhausted through the opening 49 and the air entrapped in front of the flanged portion 22a of the piston 22 is exhausted through the above described passageways controlled by the valve assemblies 32 and 34. Although the air entrapped below the flanged portion 22a of the piston 22 can be easily exhausted through the interface between the annular wall 42 and the lower end of the cylinder 20, the lower end of the cylinder 20 can be provided with apertures or spaced notches to improve the fluid communication between the lower end of the chamber 16 and the interior of the cylinder 20 when the cylinder 20 is moved to the position illustrated in FIG. 2.

The tool 10 remains in the position shown in FIG. 2 until such time as only the safety valve assembly 32 or both the assembly 32 and the manually controlled valve assembly 34 are restored to the condition shown in FIG. 1. At this time, compressed air is supplied to the lower end of the chamber 16 to again provide an upwardly directed component of force which shifts the cylinder 20 upwardly until the upper end of this cylinder engages the resilient valve seat 28 to close off communication between the interior of the cylinder 20 and the upper portion of the chamber 16. During this upward movement, the valve operator plate 75 is engaged by the upper end of the cylinder 20 and is moved upwardly against the force of the compression spring 70 so that the valve element 66

is moved out of engagement with the O-ring 74 and into the position shown in FIG. 1. This places the upper portion of the interior of the cylinder 20 in communication with the atmosphere through the openings 75a, the 5 passageway 68, the opening 62, the recess 72, the bore 78, the radial passageways 80 and the passageway 79. This exhausts the compressed air entrapped between the upper end of the piston 22 and the valve seat 28 so that the compressed air acting on the lower surface of the flanged portion 22a of the piston 22 is effective to raise the piston to the position illustrated in FIG. 1 in which the upper end thereof engages the valve operator plate 75 as a stop. As the piston 22 moves upwardly, the blade 24 is retracted in the drive track to permit the magazine assembly to advance the next fastener to be driven into the drive track. Thus, in response to each actuation of the valve assemblies 32 and 34, the piston 22 is driven through a single power stroke during which a fastener supplied to a drive track is driven into a workpiece.

Although the present invention has been described in conjunction with a single embodiment thereof, it should be understood that numerous other modifications and embodiments may be provided by those skilled in the art which will fall within the spirit and scope of the principles of this invention.

What is claimed as new and desired to be secured by Letters Patent of the United States is:

1. In a fastener driving apparatus, a housing defining a chamber continuously supplied with compressed air, a cylinder movably mounted in said chamber and including a flanged portion in sliding engagement with the wall of said chamber, a piston slidably mounted in said cylinder, a valve seat normally engaged by said cylinder to prevent communication between said chamber and the interior of said cylinder, first means for continuously connecting one side of said flanged portion to the atmosphere, and second means including valve means for selectively supplying compressed air to and exhausting compressed air from the other side of said flanged portion to shift said cylinder into and out of engagement with said valve seat, thereby to provide means for selectively admitting compressed air from said chamber into said cylinder to drive said piston.

2. In a fastener driving tool, a housing defining a chamber including an enlarged portion adapted to receive compressed air, a cylinder slidably mounted in said enlarged portion, a piston including a larger diameter upper portion slidably mounted in said cylinder and a lesser diameter lower portion slidably mounted in said chamber, a fastener driving element secured to said lower portion of said piston and extending outwardly from said chamber, a valve seat normally engaged by the upper end of said cylinder to close off communication between the upper portion of the interior of said cylinder and the chamber, means for shifting said cylinder relative to said valve seat to selectively admit compressed air from said chamber into the upper end of said cylinder to actuate said piston and said driving element, and means for selectively admitting compressed air to the lower end of said cylinder between the upper and lower portions of said piston to provide means for retaining said piston to a position in proximity to said valve seat.

3. In a fastener driving tool, a housing defining a chamber including a lower portion of lesser diameter and an upper portion of greater diameter to which compressed air can be supplied, a cylinder movably mounted in said greater diameter portion, a piston including an upper portion slidably mounted in said cylinder and a lower portion slidably mounted in said lesser diameter portion of said housing, a valve seat disposed adjacent the upper end of said cylinder, first means for supplying compressed air to the lower end of the greater diameter portion of said chamber to force the upper end of said cylinder into engagement with said valve seat and to elevate said piston, and second means for connecting the lower end of said greater diameter portion to the atmosphere to move

said cylinder out of engagement with said valve seat so that compressed air in the upper end of said greater diameter portion of said chamber enters the upper end of said chamber and forces said piston downwardly.

4. In a fastener driving tool, a housing defining a chamber to which compressed air can be supplied, a cylinder mounted in said chamber for movement between first and second axially displaced positions, a valve seat carried on said housing adjacent the upper end of said cylinder and adapted to close the open upper end of said cylinder, a driver actuating piston movably mounted in said cylinder, valve means operable to a first setting for supplying compressed air to the lower end of said chamber to force said cylinder to said first position in which the upper end of said cylinder engages said valve seat to close off communication between the interior of said cylinder and said chamber, said valve means in said first setting also supplying compressed air into the lower end of said cylinder to elevate said piston within said cylinder, said valve means also being operable to a second setting in which the lower end of said cylinder is connected to the atmosphere to permit said piston to be moved downwardly and in which the lower end of said chamber is connected to the atmosphere to permit the compressed air in said chamber to move said cylinder into said second position in which the upper end of said cylinder is out of engagement with said valve seat, thereby admitting compressed air from said chamber into the upper end of said cylinder to drive said piston downwardly.

5. A fastener driving tool comprising a housing defining a pair of axially aligned cylindrical chambers of different diameters, the upper of said chambers having a greater diameter and being adapted to receive a body of compressed air, the lower of said chambers being of lesser diameter and being connected to said upper chamber by an annular wall formed in said housing; a cylinder slidably mounted in said upper chamber; a first sealing means carried on said cylinder in sliding engagement with said upper chamber; a piston slidably mounted in said two chambers and being of a length greater than the axial length of said upper chamber, said piston including an upper flanged portion slidably mounted in said cylinder and a lower portion slidably mounted in said lower chamber; second sealing means carried on said flanged portion in sliding engagement with said cylinder; third sealing means disposed between said lower portion of said piston and said lower chamber; a valve seat carried on said housing adjacent the upper end of said cylinder; and valve controlled means for selectively supplying compressed air to and exhausting compressed air from the two chambers in the space bounded by said first, second, and third sealing means to shift said cylinder relative to said valve seat and to reciprocate said piston relative to said cylinder.

6. The fastener driving tool set forth in claim 5 in which said valve controlled means includes a passageway opening into said upper chamber adjacent said annular wall and in which said cylinder moves between two spaced positions, in one of which positions the upper end of said cylinder engages said valve seat and in the other of which positions the lower end of said cylinder engages said annular wall.

7. The fastener driving tool set forth in claim 5 including an exhaust valve assembly carried on said housing in communication with the interior of said cylinder, and means controlled by the shifting movement of said cylinder for operating said exhaust valve assembly.

8. In a fastener driving tool, a housing defining a chamber adapted to receive compressed air and having a first opening, a cylinder movably mounted within said chamber, a piston slidably mounted in said cylinder, a cap having a second opening and detachably mounted on said housing to close said first opening, a resilient valve seat adapted to be engaged by the upper end of said cylinder, an exhaust valve assembly mounted in said second opening for controlling communication between the interior of said cylinder and the atmosphere, means including said

exhaust valve assembly for securing said valve seat on said cap, and means for selectively moving said cylinder into and out of engagement with said valve seat.

9. In a fastener driving tool, a housing defining a chamber adapted to receive compressed air, a cylinder movably mounted in said chamber, a piston movably mounted in said cylinder, a valve seat normally engaged by the upper end of said cylinder to close off communication between the interior of the cylinder and said chamber, means for shifting said cylinder into and out of engagement with said valve seat to selectively admit air into said cylinder to operate said piston, said housing also providing an exhaust passageway opening into said chamber in a position aligned with said cylinder, valve means, resilient means biasing said valve means toward a position closing said passageway, and a valve operator connected to said valve means and positioned between said valve seat and said cylinder in the path of movement of said cylinder to operate said valve means to a position opening said passageway in response to movement of said cylinder toward said valve seat.

10. In a fastener driving tool, a housing defining a chamber having an upper opening and adapted to receive compressed air, a cylinder movably mounted in said chamber, a piston movably mounted in said cylinder, a cap mounted on said housing to close said opening and including an exhaust passageway, valve means carried on said cap, resilient means biasing said valve means to a position closing said passageway, a valve seat fixedly secured to said cap and normally engaged by said cylinder to close off communication between the interior of the cylinder and said chamber, means for shifting said cylinder toward and away from said valve seat to move said cylinder into and out of engagement with said valve seat to selectively admit air into said cylinder to operate said piston, and means connected to said valve means and actuated by engagement with said cylinder during movement of said cylinder toward engagement with said valve seat for moving said valve means against said resilient means to a position opening said passageway.

11. In a fastener driving tool, a housing defining a chamber adapted to receive compressed air, a valve seat carried on said housing, a cylinder mounted in said chamber and movable into and out of engagement with said valve seat to control communication between said chamber and the interior of said cylinder, a piston slidably mounted in said cylinder, means for shifting said cylinder to move the upper end of said cylinder out of engagement with said valve seat to permit the compressed air in said chamber to drive said piston and for shifting the upper end of said cylinder into engagement with said valve seat, an exhaust valve carried on said housing and including an inlet aligned with the interior of said cylinder, resilient means continuously urging said exhaust valve to a closed condition, and a valve operator secured to said exhaust valve and disposed in the path of movement of said cylinder to be engaged by the upper end of said cylinder when the upper end of the cylinder engages said valve seat, engagement of said valve operator by said cylinder maintaining said exhaust valve in an open condition in which the interior of said cylinder is connected to the atmosphere.

12. In a fastener driving tool, a housing defining a chamber having an opening and adapted to be supplied with compressed air, a cylinder movably mounted in said chamber, a piston including at least a portion slidably mounted in said cylinder, a cap mounted on said housing in axial alignment with said cylinder and closing said opening, a resilient valve seat carried on said cap and adapted to be engaged by the upper end of said cylinder to prevent communication between the exterior of said cylinder and the chamber, means for shifting said cylinder out of engagement with said valve seat to admit compressed air from said chamber to drive said piston and for then shifting said cylinder into engagement with

said valve seat to entrap compressed air within said cylinder between said cap and said piston, said cap including means defining a passageway extending between the interior of said cylinder and the atmosphere, valve means for controlling the flow of air through said passageway, resilient means normally urging said valve means toward a closed position to prevent communication between the atmosphere and the chamber, and valve operator means connected to said valve means and adapted to be engaged by the upper end of said cylinder, said resilient means closing said valve means in response to said cylinder moving away from said valve seat and said valve operator means opening said valve means to exhaust the compressed air entrapped in said cylinder in response to the upper
